UNITED STATES PATENT OFFICE

131,152

DESIGN FOR A COMBINATION KNIFE AND GAUGE

Nellie Jacobs, Brooklyn, N. Y.

Application October 24, 1941, Serial No. 193,882

Term of patent 7 years

To all whom it may concern:

Be it known that I, Nellie Jacobs, a citizen of the United States and resident of Brooklyn, New York, in the county of Kings and State of New York, have invented a new, original, and ornamental Design for a Combination Knife and Gauge, of which the following is a specification, reference being had to the accompanying drawing, forming a part thereof, and of which Figure 1 is a perspective view of a combination knife and gauge showing my new design, Fig. 2 is a top plan view thereof, and Fig. 3 is a view in side elevation thereof.

The characteristic features of my design reside in the specific configuration of the gauge in association with the knife blade and handle as shown in the drawing.

I claim:

The ornamental design for a combination knife and gauge, substantially as shown and described.

NELLIE JACOBS.
